UNITED STATES PATENT OFFICE.

GEORGE H. ELLIS, OF ST. PAUL, MINNESOTA.

IMPERVIOUS PAPER BOARD AND PROCESS FOR MAKING THE SAME.

Application filed March 26, 1923. Serial No. 627,689.

The object of my invention is to provide a paper board which is impervious to moisture and air, and free from characteristics which will injure food or other products in contact therewith. A further object is to produce such a board of durable character cheaply and economically.

It is also my object to provide such a board with surfaces which are adapted to receive printing or other desirable trade dress thereon.

The increased demand for paper board cartons and packing cases as a substitute for wooden boxes has resulted in attempts to produce a paper board impervious to air and moisture as well as free from odor detrimental to the contents, and without oiled or glazed surfaces, which make printing upon the exterior of the carton difficult or unsightly.

It is a matter of common knowledge that paraffine has been used to water proof such cartons and that cartons have also been produced by pasting or cementing ordinary paper over water proof fiber sheets. The latter method is laborious and expensive, while the paraffine is apt to rub or chip off the outer surface and make printing or other trade dress thereon unsightly.

My present invention makes the use of paraffine unnecessary, and, as compared with the built up paper board above mentioned, eliminates much labor and expense, and results in a tough, light impervious paper board which is both durable and sightly, as well as adapted to receive printing or other marks or illustrations.

Referring to the accompanying drawings, which illustrate diagrammatically a paper machine suitable for carrying out the process of the present invention in the manufacture of my improved, impervious board, Figure 1 is a side elevation of one end of the machine and Figure 2 is a transverse section through one of the cylinder moulds and the adjacent vat.

The machine is of a well known type, having a series of cylinder moulds indicated by the numerals 1 to 5 inclusive, said cylinders being severally mounted in vats 6 to 10. Paper stock which has been prepared in the beaters, is pumped into the several vats through pipes 11 and partially submerges the cylinder moulds. The moulds are journaled on suitable shafts in the ends of the vats and consist of a grid frame work 12

(Fig. 2) supported on suitable wheels 13, and coarse mesh backing wire 14 and an outer fine mesh wire 15 through which the excess water from the paper stock passes into the interior of each cylinder. Water passes out from within the cylinders through suitable weirs (not shown) in the ends of the cylinders.

As liquid from the vat flows inwardly 65 through the wire covering of each cylinder mould, the fibrous pulp is deposited on the exterior of the wire 15 and forms the paper web. An endless felt belt 16 is pressed upon the upper periphery of the cylinder moulds 70 by a series of couch rolls 17, said belt being driven by suitable means (not shown). The felt 16 is carried around a drum 18 near one end of the machine, and after running over a suitable supporting roller, passes between 75 a pair of making rolls 19, where its upper surface is brought in contact with the lower surface of an upper felt belt 20. The felts 16 and 20 carry the paper web between their adjacent surfaces to a pair of suction rolls 80 21 where a large amount of the moisture is withdrawn from the web. From the suction rolls 21 the web is carried between squeezing rolls and then through a series of press rolls to the drying cylinders in the 85 usual manner.

My improved board, made in a machine of the above described class, is composed of a plurality of layers of paper stock with an interposed layer of impervious, adhesive 90 stock. For the impervious and adhesive stratum of the board, I prefer to use stock made in accordance with the specification of my Patent No. 1,449,221, dated March 20th, 1923, insulating boards and process of making the same. The bitumen used in the impervious layer of my improved board is liquid at normal temperatures and does not harden or become brittle in the finished product. I have found in practise that such stock may be used as hereinafter described without gumming the mechanism of a paper machine and yet this stock, when applied between layers of ordinary paper stock, adheres thereto and produces a strong and 100 durable board, which is most desirable for making cartons and packing cases.

Obviously, it would be impracticable, if not impossible, to make, in a cylinder machine, paper board composed entirely of the 110 sticky, impervious stock made by my above described patented process because the bitu-

men in the web would gum up the felt and rolls of the machine. However, in the present process, I incorporate the impervious layers between layers of nonadhesive paper stock in such a manner that only the latter layers come in contact with the felt, and rolls of the machine.

To this end, as the felt 16 passes successively over the upper periphery of the cylinder moulds 1, 2, 3, 4, and 5, a layer of ordinary paper pulp is supplied to the end cylinders while the above described impervious pulp is supplied to one or more of the intermediate cylinders so that the non-adhesive layers protect the felt and rolls of the machine from the bituminous material.

To secure this result, the pulp supplied to the vats 6, 7 and 10 is of the common paper stock, which is pervious and nonadhesive, while the stock supplied to the vats 8 and 9, is preferably prepared as described in my above mentioned prior patent, that is, the pulp in the vats 8 and 9 is impregnated or coated with bitumen so that the paper web formed therefrom is adhesive and impervious to moisture and air. Thus, as the felt 16 passes over the cylinder moulds 1 and 2, layers of pervious, nonadhesive stock are applied to the felt. The web thus formed is now carried by the felt over the moulds 3 and 4, where the impervious, sticky layers are placed upon the nonadhesive layers. Finally, another layer of pervious material is applied by the mould 5 to the adhesive material so that the felt 20, which is later pressed upon the upper surface of the web, is separated from the adhesive layers by a layer of nonadhesive paper stock. A box board is thus formed in a single operation which, when passed through the usual hot or finishing rolls, is highly impervious to moisture and air and is, during the process, prevented from adhering to the parts of the cylinder machine.

Obviously, the number and thickness of the pervious and impervious layers incor-

porated in the board, may be varied as desired, without departing from the spirit of my invention.

Having described my invention and what I claim as new and desire to protect by Letters Patent is:

1. The process for making an impervious paper board, which consists in first applying a web of absorbent nonadhesive stock to the felt of a cylinder paper machine, then depositing an impervious adhesive web containing liquid bitumen on said first mentioned web in said machine and subsequently applying a web of pervious stock to the exposed surface of said adhesive web and finally compressing and drying said webs to form a multiple ply board suitable for making boxes.

2. The process for making an impervious paper board, which consists in first applying a web of nonadhesive stock to the felt of a cylinder paper machine, then depositing a web of adhesive material containing liquid bitumen upon said first mentioned web and finally applying a web of nonadhesive stock to the exposed surface of said web containing bitumen.

3. The process of making an impervious paper board which consists in forming a web of nonadhesive stock, then pressing a web of impervious, adhesive stock impregnated with liquid bitumen on said first mentioned web; then molding a web of nonadhesive stock on the exposed surface of said impervious web and finally compressing and drying said webs into a multiple ply board suitable for making boxes.

4. A box board comprising a plurality of layers of absorbent stock and an intermediate self cohering layer of saturated paper stock forming an integral sheet having pervious surfaces with a core waterproofed with bitumen which remains fluid at normal temperatures.

In testimony whereof, I have hereunto signed my name to this specification.

GEORGE H. ELLIS.
